UNITED STATES PATENT OFFICE.

FRANK MOSSBERG, OF ATTLEBORO, MASSACHUSETTS, ASSIGNOR TO FRANK MOSSBERG COMPANY, A CORPORATION OF RHODE ISLAND.

WRENCH.

1,078,059.

Specification of Letters Patent. Patented Nov. 11, 1913.

Application filed October 19, 1912; Serial No. 726,760; Renewed October 1, 1913; Serial No. 792,875.

To all whom it may concern:

Be it known that I, FRANK MOSSBERG, a citizen of the United States, residing at Attleboro, in the county of Bristol and State of Massachusetts, have invented certain new and useful Improvements in Wrenches, of which the following is a specification.

My invention relates to ratchet wrenches and has for its primary objects the provision of a body capable of construction at a minimum expense, and adapted to inclose the operative parts; to make it possible to reverse the direction of travel of the ratchet head; and to provide a reversal mechanism convenient to operate.

The invention accordingly consists in the features of construction, combinations of elements, and arrangement of parts which will be exemplified in the construction hereinafter set forth; and the scope of the application of which will be indicated in the appended claims.

In the accompanying drawings which form a part of this specification,—Figures 1 and 2 are front and side elevations respectively of a ratchet wrench embodying my invention, part of the handle being broken away, Fig. 3, a view similar to that of Fig. 1, but showing a portion of the front plate broken away, Figs. 4, 5 and 6, sections on lines *w w*, *x x* and *y y* respectively of Fig. 1, and Fig. 7, a section on line *z z* of Fig. 3.

Like reference characters indicate like parts throughout the views.

My wrench is composed of a broad tapering head portion A and a narrow handle portion B, the whole consisting of a front plate C and a back plate D similar to each other in all respects, provided respectively with inwardly directed marginal flange portions *c* and *c'*; transversely disposed depressed portions in the head, *d* and *d'*; and longitudinally disposed depressed portions, *e* and *e'*, in the handle. The plates C and D are also provided in their head portions respectively with circular openings *f* and *f'*; adjacent rectangular perforations *g* and *g'*; transverse openings *h* and *h'* in the transverse depressions; and perforations *k* and *k'* respectively in the handle portion. In the head portion of said plates are respectively provided perforations *l* and *l'* to receive rivets *m*. Rivets *n* in perforations *k* and *k'* also assist the first mentioned rivets in holding the edges of the flanges *c* and *c'* in

contact, and the combined plates will be seen to be hollow and form a complete housing for the parts now to be described. The plates C and D are made of comparatively thin metal capable of being bent or depressed with comparative ease with suitable tools, thus avoiding the expense of material, labor in finishing, and excessive weight inherent in wrenches whose bodies are of solid material.

A cylindrical ratchet head or body O is provided with a central angular opening *o*, and an annular series of peripheral teeth *o'* midway its front and rear faces. This head turns loosely in the openings *f*, *f'* of the head portion A, and is secure against detachment by the side faces of the teeth which slidably bear against the inner faces of the front and back plates C and D. The opening *o* of the ratchet head is particularly adapted to receive the reduced squared end *p* of a removable socket P. It will be understood that the bodies of these sockets P are of varying sizes, while their shanks or ends *p* are substantially uniform in size.

To facilitate the retention of the socket end, particularly in case of slight variations of dimensions, the head O is recessed longitudinally of the opening *o* as at Q, and in its adjacent front and rear sides, as at *q*, and a flat spring *q'* applied to the recess Q; the ends *q''* of the spring being bent at substantially right angles to the spring. These ends form ears provided with teats *q'''* adapted to enter the recesses *q* whereby the spring is assisted in retaining its position relatively to the slot or recess Q. The spring normally extending outwardly from the surface of the head O to frictionally engage the end of the socket. Adjacent the head O is a pin R whose squared reduced ends reenter the openings *g* and *g'* of the plates of the head, and upon this pin is pivotally mounted a pawl S provided upon its rear with two interspaced shoulders *s* and upon its forward margin with two interspaced teeth *s'* adapted to alternately register intermediate the teeth *o'* when the pawl is rocked. In broken lines is shown a second position of the pawl as rocked.

In the portion of the head adjacent the handle is located transversely a plate T whose reduced ends *t* enter openings *t'* and *t''* in the plates C and D respectively. This plate is provided with a central opening *t'''*.

Passing loosely through the opening t^3 is a shank portion u of a lever U having an enlarged head u' provided with a pointed end u^2 . A spring u^3 surrounds the shank u and has one end bearing against the plate T and its other end against the head u' of the lever. The portion u' of the lever is provided with a longitudinal slot u^4 . Washers u^5 are located at each side of the head. A pin V passes loosely through the washers and the openings h h' and u' , and has upon its opposite ends knurled heads v , so that by the thumb and finger the lever U may be transversely vibrated from the position shown in full lines in Fig. 2 to the position shown in broken lines therein, thus reserving the relative position of the teeth s' with relation to the teeth o' on the ratchet head.

It will be observed that by vibrating the handle one of the teeth s will engage and rotate the ratchet head in one direction only, while when the other tooth s of the pawl has been shifted into contact with the ratchet teeth by means of the lever U the ratchet head will be impelled in the opposite direction at each reciprocation of the handle. It will be further observed that all the operating parts are inclosed within the housing formed by the plates C and D and their respective flanges, and that the assemblage of the parts is firm, simple, and free from the use of solder, and that the resulting structure is comparatively light.

I claim:—

1. In a ratchet wrench, a head portion having a rigid handle, a ratchet head rotatably mounted in bearings in said head

portion and having socket opening and peripheral teeth, a pawl pivotally mounted in the head portion for rocking movement and having interspaced shoulders, a bodily movable lever having a longitudinal slot, a spring around the shank of said lever, a guide for said shank against which said spring has a bearing, the head portion being provided with transverse openings and transverse depressed portions opposite thereto and a pin passed loosely through said openings and through the longitudinal slot of the lever and having heads disposed in said depressions for transversely vibrating said lever.

2. In a ratchet wrench, a head portion having a rigid handle, a ratchet head rotatably mounted in bearings in said head portion and having socket opening and peripheral teeth, a pawl pivotally mounted in the head portion for rocking movement and having interspaced shoulders, a bodily movable lever having a longitudinal slot, a spring around the shank of said lever, a guide for said shank against which said spring has a bearing, the head portion being provided with transverse openings and a pin passed loosely through said openings and through the longitudinal slot of the lever, and washers on said pin upon opposite sides of said lever.

In testimony whereof I have affixed my signature in presence of two witnesses.

FRANK MOSSBERG.
